Patented Aug. 15, 1922.

INVENTOR
FREDERICK L. DAVIDSON.

BY *Frederick L. Davidson*
ATTY.

UNITED STATES PATENT OFFICE.

FREDERICK LELAND DAVIDSON, OF HALIFAX, NOVA SCOTIA, CANADA.

DISH-WASHING MACHINE.

1,426,260.

Specification of Letters Patent. Patented Aug. 15, 1922.

Application filed July 8, 1921. Serial No. 483,339.

To all whom it may concern:

Be it known that I, FREDERICK LELAND DAVIDSON, a subject of the King of Great Britain, and resident of the city of Halifax, 5 in the Province of Nova Scotia and Dominion of Canada, have invented certain new and useful Improvements in Dish-Washing Machines, of which the following is a specification.

10 This invention relates to improvements in dish-washing machines of the type in which the plates are held in racks and washed by water splashed against them by rotary splashers, and the objects of the invention are generally to improve the construction of the splashing device to enable it to better perform the functions required of it.

15 The splashing device consists essentially of a particular form of a hub having diametrically opposite vanes, one of which is curved and provided with a flattened portion so as to splash a larger quantity of water against the plates in the washing machine.

20 With the above and other objects in view, the invention consists essentially of the improved construction particularly described and set forth in the following specification 30 and accompanying drawings forming part of the same.

In the drawings:

25 Figure 1 is an elevation in longitudinal section of a dish washer equipped with my improved splashing device.

Figure 2 is a cross section of the same.

30 Figure 3 is a perspective view of two of the splashing members, mounted on different angles on the shaft.

40 Figure 4 is a perspective view of one of the splashers.

In the drawings, like characters of reference indicate corresponding parts in all the figures.

45 Referring to the drawings:

A represents a dish washing machine of the type described in my previous Patent No. 1,360,192, issued November 23, 1920,

which comprises a casing 10 having a reciprocal plate holder 11 and racks of inverted 50 U-shape 12 designed to support the plates.

The casing carries two bearing members 13 on which is rotatably mounted a shaft 14 having an end extending through the wall of the casing 10 and provided with a 55 gear 15 designed to mesh with a larger gear 16 having a crank 17 through which the shaft may be suitably rotated.

On the shaft 14 there is mounted a plurality of splashers B which are here shown 60 in two different positions on the shaft, but it must be understood may be mounted on any angles which would be found to be adapted to splash more water against the 65 plates.

The splasher B each comprise a hub 18 formed with two diametrically opposite vanes 19 and 20, and provided with an orifice which is engaged by a set screw 21 designed to bear against the shaft 14 and secure the splasher B thereon to the desired angle. The vane 19 of the splasher extends straight from the hub, while the vane 20 is curvilinear in longitudinal section and provided with a flattened portion 21, which 75 is designed to splash a larger quantity of water against the plates mounted on the racks 11 and 12.

It will be seen that when this splasher is used in connection with a dish washing machine as illustrated, that the water will be splashed against the plates in the racks 11 and 12, and no water will gather between the vanes of the members, as would be the case when the splasher is formed of four boards, 85 as is usually used in connection with these washers.

It will be seen that the casing may also be provided with an outlet 22 through which the water in the casing may be let out.

90 As many changes could be made in the above construction and many apparently widely different embodiments of my invention within the scope of the claim, constructed without departing from the spirit 95 or scope thereof, it is intended that all mat-

ter contained in the accompanying specification and drawings shall be interpreted as illustrative and not in a limiting sense.

What I claim as my invention is:

- 5 In combination with a washing machine of the kind described, a rotary shaft, a splasher on the shaft comprising a hub, with two diametrically opposite vanes extending therefrom, one of the vanes being

curved longitudinally, and a flattened portion on the outer end of the curved vane.

In witness whereof I have hereunto set my hand in the presence of two witnesses.

FREDERICK LELAND DAVIDSON.

Witnesses:

J. L. MACKINNON,
H. D. KEMP.
